RING RIDGE REAMER

Arthur C. Toske, Jacksonville, Fla.

Application March 9, 1950, Serial No. 148,568

1. Claim. (Cl. 77-2)

1 This invention relates to a ring ridge reamer. In the art of internal combustion engine maintenance and repair, it is a well known fact that piston rings wear a cylinder to a greater extent than the piston itself wears the cylinder, and since the ring travel terminates short of the upper end of the cylinder, a ring ridge or annular shoulder is formed upon the cylinder wall at the upper end of the cylinder.

Before the installation of new piston rings, it is necessary that the ring ridge be removed, and the present invention has for its main object the provision of a hand-operated tool which will accomplish removal of said ring ridge speedily and with ease, so as to make the diameter of the cylinder opening uniform throughout the length of said cylinder.

Another important object is to provide a tool of the type stated which will, after removing the ring ridge, chamfer or bevel the sharp edge at the extreme top of the cylinder for the purpose of safer and easier installation of the new rings.

Still another object is to provide a tool as described which will be capable of mounting directly in the piston which has just been removed from the cylinder, said piston being inserted in the cylinder in inverted position with the tool mounted inside it, after which the tool and piston is readily rotatable for the purpose of scraping away the ring ridge.

Still another object is to provide a tool as described readily adjustable to fit cylinders of different diameters.

Another important object is to provide a tool of the type stated which can be manufactured at low cost, but which will be quite durable, embodying a minimum of parts simply arranged.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings

Fig. 1 is a top plan view of the tool mounted within a piston, a wrench inserted in the tool for rotating the same being shown in section.

Fig. 2 is a side elevational view of the tool, a piston in which the tool is mounted and a cylinder in which a ring ridge is to be reamed out being shown in vertical section.

2

Fig. 3 is a section taken substantially on line 3—3 of Fig. 1.

Fig. 4 is a section taken substantially on line 4—4 of Fig. 3.

Fig. 5 is a section taken substantially on line 5—5 of Fig. 3.

Fig. 6 is a section taken substantially on line 6—6 of Fig. 3, portions being broken away.

Referring to the drawings in detail, there has been illustrated in the drawings a portion of a cylinder wall 1 merging at its upper end into the upper surface 2 of the cylinder block. The ring ridge 3 to be removed, said ridge having been formed by piston ring wear, appears at the upper end of the cylinder wall as readily seen in Figs. 2 and 3.

To accomplish removal of the ring ridge 3, I provide a manually operated tool including the cylindrical body 4 one end of which is threaded 20 as at 5, the body 4 being formed intermediate its ends with a transverse opening 6 and, adjacent and crosswise of said opening, another transverse opening 7.

Either of these openings is adapted to receive 25 a cross pin 8 one end of which projects from the body 4 so as to engage, for rotation with the body, a hand-operated adjusting wheel 9 having the central opening to permit the wheel to be removably slipped over the body 4, there being formed radially of said opening a pin-receiving recess 10, in which the pin 8 engages so that one using the tool can rotate the body 4 by rotation of the adjusting wheel 9, to make necessary adjustments in a manner to be described in detail hereinafter.

The threaded end 5 of the body 4 is threadably engaged in the threaded socket 11 of a bit holder 12 the outer end of which is formed with the stop shoulder 13 that seats against the upper surface 2 when the tool is in use. The stop shoulder 13 is curved longitudinally as best seen from Figs. 1 and 2, in approximate correspondence with the curvature of the cylinder opening.

Accordingly, rotatable adjustment of the body 45 4 will shift the bit holder 12 radially of the cylinder opening, the bit holder 12 being kept against rotation by engagement of the stop shoulder 13 with the upper surface 2 of the cylinder block.

Formed in the outer surface of the bit holder 50 12 is a vertically disposed bit-receiving recess 14 in which is removably mounted a bit or cutter 15, the upper end of which can be enlarged as best seen in Fig. 3 so as to permit the cutting edge of said bit to curve outwardly at its upper end as best seen at 16 in Fig. 3, to bevel or cham-

fer the sharp extreme top edge of the cylinder opening after the ring ridge 3 has been removed by said bit.

In the opposite end of the body 4 I form an end recess 17 which in the present instance is smooth-walled, for insertion of a dowel 18 the other end of which is removably positioned in an extension sleeve 19 inserted in the smooth-walled socket 20 formed in a bit holder 21. The extension sleeve 19 can be one of a set of such sleeves varying in length, so as to swiftly adapt the tool for reaming ring ridges on cylinders of any diameter, fine adjustments being made by means of the hand wheel 9.

The bit holder 21 is, in general, shaped like the bit holder 12, being different therefrom only in that it has a smooth-walled socket as distinguished from the bit holder 12, the body receiving socket of which is threaded.

Formed upon the outer end of the bit holder 21 is the arcuate stop shoulder 22 seated upon the top surface 2 of the cylinder block, at a location diametrically opposite from the engagement of said surface 2 by the other stop shoulder 13.

Below the stop shoulder 22, the bit holder 21 is formed with a bit-receiving recess 23 in which is positioned the bit 24 formed like the bit 15.

Adapted to be removably slipped over the medial portion of the body 4 is the upstanding stem 25 having the body-receiving opening 26 formed in its lower end. Stem 25 in the present instance has an enlarged head 27 at its upper end, which head is formed with a wrench-receiving, noncircular socket 28 in which can be inserted the working end 29 of a conventional wrench.

Of course, instead of a female wrench connection 28, a wrench-receiving male member can be formed upon the head 27, this being believed sufficiently obvious as not to require special illustration.

From the description which has been so far provided, it will be apparent that the entire tool is capable of complete disassembly, for insertion of the pin 8 at different locations lengthwise of the body 4, and for insertion of any extension sleeves or wrench stems 25 found most desirable for the particular job.

In any event, the tool is assembled directly within the piston 30 just removed from the cylinder 1, the bit holders being mounted directly within the conventional piston pin bosses 31 of said piston.

After the tool has been so mounted with the piston 30 inverted, the inverted piston, which will now constitute a hollow, cup-shaped boring head, is re-inserted in the cylinder opening, as shown in Fig. 2.

Necessary adjustments are now made by means of the wheel 9, so as to engage the cutters against diametrically opposite portions of the ring ridge, and by means of an ordinary wrench, the entire piston 30 and tool mounted within said piston is rotated within the cylinder opening, so as to cut away said ring ridge. As the cutting operation continues, further adjustments are made as necessary by means of the hand wheel 9.

After the ring ridge 3 has been scraped fully away, thus to make the diameter of the cylinder opening uniform throughout, it will be found that the bits will have formed a beveled or chamfered top edge upon the cylinder opening, for safer and easier installation of the new piston rings.

What is claimed is:

A tool for reaming a cylinder bore to remove from the wall thereof an annular ridge resulting from the wear of piston rings against the wall of said bore, said tool comprising an open-ended elongated hollow head of a diameter substantially equal to the diameter of the cylinder bore, said head having horizontal openings extending transversely therethrough intermediate the ends thereof, tool bit holders mounted in the openings for movement therein along an axis which lies perpendicular to the longitudinal axis of the head, one of said tool bit holders having a threaded socket, tool bits mounted in the holders adjacent the periphery of the head for movement with said holders including a cylindrical body having one of its ends threaded in said hollow socket, the opposite end of said cylindrical body being rotatably mounted in the other tool bit holder, an adjusting wheel secured to said cylindrical body and accessible through said open end of said hollow head for effecting rotation of said cylindrical body, advancing or retracting said tool bits radially with relation to the head, as said adjusting wheel is rotated, and means carried by the tool bit advancing and retracting means and extending through one end of the head, for rotating said head about its longitudinal axis and moving the tool bits in contact with said ridge.

ARTHUR C. TOSKE.
